UNITED STATES PATENT OFFICE.

JOHN C. BUCKBEE, OF CHICAGO, ILLINOIS.

MATERIAL-BUNKER PLANT.

Application filed October 17, 1927. Serial No. 226,591.

This invention relates to improvements in material bunker plants and more particularly to a new and novel arrangement of overhead bins or bunkers whereby different mixtures of the contents of the several bins can be discharged at one or more loading points.

The object of the invention is to provide a convenient and efficient means for the handling of materials for retail delivery, such as those used in making of concrete.

A further object of the invention is to provide an arrangement of inter-related bins whereby the contents from a given number of bins may be delivered in the required amounts into a common receptacle or batching machine and thence discharged by gravity into a waiting vehicle for withdrawal to the place of use.

A preferred embodiment of the invention is disclosed in the accompanying drawings, in which

Figure 1 is a top plan view of the bins.

Figure 2 is a view in side elevation showing a typical arrangement of the bins.

Figure 3 is a view in vertical section taken on line 3—3 of Figure 2.

It is to be understood at the outset that the arrangement and structural design of the apparatus herein disclosed is only intended to be typical of plants for the handling of material, and therefore I do not desire to attach undue importance to details of construction since considerable latitude is permissible in this respect.

In general, a plant embodying my invention consists of a plurality of bins 1 arranged in two rows parallel with each other and spaced relatively close together. Each row preferably consists of four bins, making eight in all, although the number may be decreased or increased, if desired, depending on the number of different materials to be handled. For instance, the least number of bins would be two, increasing to eight or more, although in the present arrangement eight is the largest number which can be considered as constituting a complete plant.

The bins are of the vertical type, being of any suitable construction and shape, although shown as cylindric for convenience. The bins are erected above the level of the ground and on a suitable supporting structure carried on posts or piers 2. The supporting frame may be of wood, structural steel or steel and concrete, as desired. The piers are arranged in four parallel rows ex-

tending longitudinally of the bins, the height of the piers and the distance between the longitudinal rows thereof being such that there is ample width and head room below the bins for three parallel driveways, viz., two outer driveways A—A passing beneath each row of bins, and a central or intermediate driveway B between the rows of bins. Manifestly such an arrangement contemplates the loading of trucks or road vehicles, although industrial or narrow gauge tracks may be laid in place of the driveways for the loading of dump cars, or even standard gauge tracks for cars of the gondola type.

The upper ends of the bins are preferably open and may be filled by any suitable apparatus available. In small plants a portable hoist may be used for loading the bins from cars on an adjacent side track, whereas large plants may be equipped with permanent hoisting and loading apparatus of any approved type, with distributing chutes to the different bins. This, however, is a matter of choice, it being simply assumed that the bins are filled from time to time, each with a different kind or grade of material.

Considering the bins as grouped in pairs from left to right, there is positioned centrally of the first and second pairs of bins a receptacle or batching machine 3 approximately at the level of the bottom of the bins. Between the second and third pairs of bins and the third and fourth are similarly located batching machines 3, the same being arranged in a row arranged centrally of the space between the two rows of bins and above the central driveway B. These batching machines have the form of open receptacles having a discharge chute or opening in their bottom wall. Referring again to the batching machine 3, around which the first and second pairs of bins are grouped, each of these bins is provided with a lateral or side delivery chute 4 near its bottom and inclined downwardly and emptying into said batching machine. Each chute 4 has a suitable gate or valve (not shown) with suitable operating mechanism for controlling the discharge of material from each bin. The same arrangement is carried out in the bins grouped about the second and third batching machines, it being noted that each bin of the second and third pairs, i. e., the intermediate pairs, has chutes 4 leading to the intermediate or center batching machine as well as to the outer or end batching machine.

nearest thereto. In addition to the lateral chutes of the batching machines, each bin has a discharge chute 5 at its bottom and immediately over the outer driveways A—A, 5 these chutes being also gate-controlled.

The operation of a plant of this character will be manifest from the following explanation: Assuming first that each of eight bins contains a different material, it 10 follows that an entire load may be taken from any one bin by driving a truck or wagon along the driveway A passing under the proper bin and filling the truck through the bottom chute 5 as though it were a single 15 loading bin.

But assuming that a mixture of materials from two, three or four different bins is required, the truck is driven along the central driveway B beneath one of the three 20 batching machines 5. If the mixture desired requires materials stored in two or more of the first two pairs of bins (at the right, Figures 1 and 2) the truck would stop under the first or right hand batching machine and 25 by operating the gates in the chutes leading to said batching machine from any two or more of these bins, the proper amount of material will be delivered into the batching machine and thence into the truck. The 30 usual practice is to fill the batching machine repeatedly with the material from the desired bins and then empty the contents into the truck. Similarly, mixtures of materials from two or more of the second and third 35 pairs of bins can be mixed and delivered through the middle batching machine 3 while the left-hand batching machine 3 delivers a mixture from any or all of the third and fourth pairs of bins. Thus it will be 40 observed that the contents of any one of the two intermediate pairs of bins can be mixed together or with the materials from one of the adjacent outermost pairs of bins, and although this arrangement does not provide for the mixing of materials from all 45 bins in the series, there is nevertheless ample flexibility to provide for a large number of different mixtures. As a practical matter, the bins would be loaded in such a manner 50 that only those materials which are ordinarily mixed would be in adjacent bins. For example, the end pairs of bins would not be filled with materials that would enter the same mixture. A knowledge of mixtures is 55 obviously essential to the proper distribution of the material bins, but this would present no particular difficulty to one skilled in the art.

By the arrangement of inter-related bins 60 and driveways herein disclosed as embodying my invention, it is possible to greatly facilitate the handling of materials, and promotes economy in its use and accuracy in proportion of different grades or sizes entering into the mixture required for the

work at hand. Moreover, it permits of savings in time required for retailing materials, since a number of trucks can be filled simultaneously not only from different bins but from the same bins.

70

As already stated, I do not wish to confine the invention to any particular design or construction of equipment used, or even to the particular materials handled, inasmuch as the scheme is applicable to the delivering of any loose materials when a mixture of two or more in given amounts is required.

75

I claim as my invention:

1. A material bunker plant comprising 80 a plurality of bins elevated above the ground and arranged in parallel rows, a plurality of parallel driveways passing beneath said bins, one under each row and one between said rows, each of said bins having a discharge opening over the driveway extending beneath the same, and a separate discharge to a point of delivery over the driveway between said rows and in common with another of said bins.

85

2. A material bunker plant comprising a plurality of loading bins elevated above the ground and arranged in parallel rows, a driveway passing beneath each row of bins, and an intermediate driveway between said rows of bins, each of said bins having a discharge opening over the driveway passing therebeneath, and a lateral discharge passage terminating at a common delivery point over said intermediate driveway, and 100 a batching device at said common point of delivery.

95

3. A material bunker plant comprising a plurality of loading bins arranged in parallel rows, a driveway extending longitudinally beneath the bins in each row, and a central driveway extending between said rows, a plurality of batching machines spaced apart between said rows of bins and above said central driveway, said bins being 105 divided into groups, each having one or more lateral discharge chutes adapted to discharge into an adjacent batching machine.

105

4. A material bunker plant comprising a plurality of bins elevated above the ground 110 and arranged in parallel rows, a plurality of parallel driveways, one passing beneath each row of bins, and a central driveway between said rows, each of said bins being adapted to contain a different material and 115 having a bottom discharge opening over the driveway extending beneath the same, and a batching device located above said central driveway and between each successive pair of opposing bins in each row, and 120 lateral chutes extending from each bin to the batching device adjacent thereto.

115

Signed at Chicago, Ill., this 14th day of October, 1927.

JOHN C. BUCKBEE.
